DESTRUCTOR

Arthur H. Mann, Nyack, N. Y., assignor to Morse Boulger Destructor Company, Inc., New York, N. Y., a corporation of Delaware

Application October 5, 1931, Serial No. 566,998

5 Claims. (Cl. 263—52)

This invention relates to incinerators or destructors, and among other objects aims to provide improved apparatus of this character for handling highly combustible materials or materials in which a rapid rate of combustion is undesirable.

The invention may be readily understood by reference to certain illustrative constructions embodying the invention and shown in the accompanying drawings.

In said drawings:

Fig. 1 is a longitudinal section through a high capacity destructor;

Fig. 2 is a longitudinal section through a destructor designed for the use of short flame fuel;

Fig. 3 is a longitudinal section through a destructor employing a long flame fuel; and

Fig. 4 is a longitudinal section through an accessory which may be employed in connection with the recovery of lead or other molten material from the material burned.

The invention here shown is embodied in incinerators or destructors designed for burning materials such as insulated copper wire where the high temperatures resulting from a rapid rate of combustion not only increase the production of objectionable smoke but also impair the quality of the copper or the like which it is desired to recover and reuse; or for burning materials containing substances which are so highly inflammable as to be practically explosive if burned at ordinary rates or temperatures such, for example, as waste lacquer thinner, films, etc.

Materials such as insulation on wire burn readily; but whether the burning be rapid or slow, large volumes of dense, disagreeable smoke are produced which, if permitted to escape, would constitute an objectionable nuisance. In the apparatus herein described the materials are burned by restricting the supply of air, so as to maintain low temperatures and to retard the rate of production of smoke, which as stated above for some materials such as insulated wire, increases with the high temperatures produced by rapid burning. The resulting smoke and fumes are then conducted away from the burning chamber and heated in the presence of additional air to effect a complete combustion of the smoke or a safe burning of highly inflammable products. The consumption of the smoke or fumes preferably occurs at a point from which little or no heat will be communicated to the original burning chamber, so as not to elevate the temperatures therein and to permit the burning to take place

slowly and at relatively low temperatures which do not injure the recoverable metal.

In Fig. 1 is illustrated apparatus designed to have a relatively high capacity wherein a large volume of smoke is developed which requires a relatively large combustion chamber for its consumption. The apparatus comprises the initial burning chamber 10 appropriately enclosed by walls 11 whose interior face generally is made from refractory material. It will be understood that the general structural features of the walls, arches, etc. conform to standard practice for apparatus of this character. Doors for charging and removing materials such as insulated wire or lead covered cable are indicated diagrammatically at 12 in the sides of the structure. The material is burned in the chamber 10 at a low rate by restricting the supply of air. This, of course, produces dense smoke which must be later consumed, but the temperatures at which the burning occurs are not so high as to deteriorate the material desired to be recovered, such as copper or lead, or such as to result in danger of explosion where highly inflammable materials are burned. The supply of air is regulated by appropriate means such as the register 12' in the door and it is therefore desirable that the chamber 10 be constructed so that unregulated quantities of air do not leak in.

The smoke or fumes then pass out of chamber 10, in this case through the passage 13, and are reheated at a point removed from the chamber 10 and supplied with additional air to effect a complete and safe combustion. The heating means is here shown as a heating chamber 14 shown with a fuel feeding and stoking door 13' and having a fuel burning grate 15 sufficiently separated from the chamber 10 by a thick bridge wall so as not substantially to elevate the temperature in the latter. It will be noted that the bridge wall is of double thickness and is provided with a passage 14' which conducts additional air to the heating chamber 14. The fuel employed is generally rubbish; but if sufficient refuse is not available, coal or other common fuels may be employed.

In passing over the fire in chamber 14, the smoke and fumes mingle with the hot gases from the chamber and additional quantities of air supplied at this point either through the grate 15 or through the additional air inlet 14', and are thereby elevated to a proper temperature to effect their complete combustion. The combustion space 16 above and leading from the burning chamber is, in this case, supplemented by an

additional burning and settling chamber 17, separated from the former by a bridge wall 17', in order to give the apparatus adequate capacity. The gases pass into the chamber 17 through the 5 downwardly extending passage 18 provided by the depending settling chamber wall. The chamber 17 is preferably larger in section than the passage 18 in order that the velocity of the gases may be substantially reduced and a settling 10 of any solid material effected in this chamber. After the smoke or fumes have been completely 15 consumed, the gases pass into the flue 19 whose draft is regulated by a damper 20.

In burning insulated copper wire, for example, 15 the temperatures are maintained sufficiently low in chamber 10 by restriction of the supply of air not to produce an objectionable scale on the copper or otherwise impair its value. The hearth 20 of the burning chamber 10 where insulated wire is burned may be either solid or of grate form which would facilitate the separation of ash from the wire. A solid or imperforate hearth is, of course, less likely to result in leakage of undesirable air than where a grate is employed. 25 Where it is desired to recover lead from the burning of lead covered cable and the like, a solid bottom is preferable. In the latter case, as shown in Fig. 1, the floor or hearth 21 is sloped to an outlet 22 through which the molten lead 30 may pass into a removable receptacle located in the enclosed chamber 23.

In Fig. 2 is shown apparatus particularly designed for the use of a short-flame fuel such as 35 coal, which requires that the smoke and fumes from the burning chamber pass into closer proximity to the fire than where a longer flame is present. The initial burning chamber 24 has an arched top 25 and the interior walls are surfaced with appropriate refractory material. At 40 one side is shown a charging door 26 and at the front end a door 27 which may be used both to charge and remove ash and other residue. In this case, a solid hearth 28 is shown sloping to an opening 29 through which molten material may 45 pass into a removable receptacle within the enclosed space 30.

The chamber 24 being enclosed, the supply of 50 air may be restricted by adjustment of the register 26' in the door to the proper degree to secure slow burning and relatively low temperatures. The smoke and fumes pass from chamber 24 through the arched passage 31 into the heating chamber 32 (whose fuel feeding and ash doors are shown in dotted lines), separated from the chamber 24 by a correspondingly lower bridge wall, and into close proximity to the fuel which 55 rests upon grate 33. An adequate heating of the smoke is thus effected not only in the chamber 32 but in passing through the heated checker brick work 34. This heating, together with the additional air supplied in chamber 32 from the grate and through the opening 32' effects a thorough burning of the smoke and fumes which is completed in the secondary combustion chamber 60 35. The products of combustion then pass into the flue 36.

In Fig. 3 is illustrated an apparatus designed 70 particularly for a long-flame fuel such as dry rubbish. The burning chamber 37 wherein the supply of air is restricted by the register 37' is shown provided with a solid hearth 38 which slopes toward the front, and the opening 39 therein is closed by a removable plug 40. With this construction any molten lead collects adjacent 75 the plug and it may be permitted to escape

from the chamber through the opening 39 by slightly raising the plug. The lead may be collected in any appropriate receptacle such as the vessel 41.

Material to be burned may be introduced and 5 residue, or ash removed, through the door 42. Flames and air for effecting consumption of the smoke and fumes are supplied from the chamber 43 having a grate 44 and sufficiently isolated from chamber 37 as not to transmit heat thereto. The 10 rubbish or other materials providing the long-flame fire may be introduced through the door 45. Ashes are collected in the ash space 46 and may be removed through the door 47 which together with opening 43' may serve to supply the 15 excess or additional air necessary to effect the combustion of the smoke and fumes.

The burning chamber 37 is provided with an arched top 48 which terminates short of the relatively high bridge wall 49 to provide the passage 20 50 through which the smoke and fumes pass. The smoke from chamber 37 and the burning gases from the chamber 43 initially mingle in the space 51 and pass through the checker brick work 52 where the heating of the smoke and fumes is 25 completed. The completion of the combustion of the smoke and fumes takes place in the secondary combustion chamber 53 from which the gases pass into the flue 54. This chamber as well as the passage 50 and space 51 are sufficiently remote 30 that little or no heat is transmitted to the burning chamber.

In Fig. 4 is illustrated one form of apparatus which may be employed in connection with the recovery of molten lead. In order to avoid the 35 entrance of an unregulated quantity of air through the opening in the hearth through which the molten lead is designed to pass, it is desirable to provide some means whereby the lead may be conveniently withdrawn while yet excluding air. 40 Moreover, it is undesirable to cast the lead into pigs by successive additions which solidify, because of the fact that the ash carried out with the lead would be in the pig instead of floated on the surface. It is, therefore, desirable to permit 45 the lead to collect and then cast it only at intervals. However, where lead is permitted to collect and partially solidify, it is often difficult again to remelt it. It is desirable, therefore, to collect the lead in such a way that it may be maintained 50 in molten condition or easily remelted. In Fig. 4 is shown an apparatus which may be easily added to any of the destructors above described. The apparatus comprises an open ended receptacle 55 in the form of a large, inclined pipe 55 which is placed in communication with the outlet 56 in the floor of the hearth 51 of the burning chamber. The molten lead drains down the inclined bottom of the pipe into a cylindrical receptacle 58 having an outlet 59 in its bottom closed by 60 a plug 60 which may advantageously be made of graphite with its end tapered to fit the outlet seat. The lead thus collects in the receptacle 58 and the lower end of the pipe 55 both of which are surrounded by the walls 61 of a heating chamber. Heat may be supplied by any appropriate means, such as by a fire on grate 62, to maintain the lead in molten condition. After sufficient lead has accumulated to form one or more standard sized pigs, the plug 60 may be raised 65 slightly by its handle 63 which is weighted to hold the plug on its seat to permit the lead to escape slowly into the mold 64 to be cast into pigs.

The means for collecting the lead without admitting cool air into the chamber and for heat- 75

ing the lead may, of course, be embodied in structures whose details vary widely from those illustrated.

Where it is desired to burn or destroy materials containing a highly inflammable substance, the initial burning likewise takes place slowly and at low temperatures by restricting the supply of air. The resulting fumes, while combustible, are not of an explosive character at their low temperatures; and when mixed with additional air and a large volume of gases from the heating chamber, they are diluted sufficiently so as not to be explosive and are thereby consumed with safety.

It will be noted that in the apparatus herein described, the mixture of the hot burning gases with the smoke and fumes takes place at a remote point so as not to accelerate the burning in the burning chamber; and the rate of burning in the latter may, therefore, be easily controlled and retarded. This results in the generation of fumes and smoke at a relatively slow rate and does not impair the value of the materials such as copper and lead which it is desired to recover. The subsequent heating of the smoke and fumes to a high temperature and the addition of air results in their complete combustion and no objectionable smoke and fumes issue from the flue of the apparatus.

Obviously the invention is not limited to the details of the illustrative constructions herein shown and described since these may be variously modified. Moreover, it is not indispensable that all features of the invention be used conjointly since various features may be used to advantage in different combinations and sub-combinations.

Having described my invention, I claim:

1. The method of burning materials containing recoverable metal which is characterized by initially burning the materials with a restricted amount of air to convert the combustible contents into smoke and gas at low temperatures so as not to injure the metal, then conducting said smoke and gases away from the point of initial burning, and heating the same with an adequate supply of air to effect a safe and complete combustion of the gases and smoke.

2. The method of burning materials containing recoverable metal which is characterized by initially burning the materials with a restricted amount of air to convert the combustible contents into smoke and gas at low temperatures so as not to injure the metal, then conducting said smoke and gases away from the point of initial burning, and mixing the same with hot burning gases and air in addition to that necessary for the said hot gases to heat the said smoke

and gases and effect complete combustion thereof.

3. The method of burning materials containing recoverable metal which is characterized by initially burning the materials with a restricted amount of air at low temperatures to drive off the combustibles in the form of gases and smoke without burning the metal, conducting such relatively cool gases away from the remaining metal and heating the same to an adequately high combustion temperature, adding air and burning the said gases and smoke at a temperature which results in complete combustion.

4. The method of destroying readily inflammable materials or materials which produce large volumes of smoke under ordinary combustion which is characterized by initially burning such materials on an imperforate hearth in a substantially closed chamber and restricting the admission of air thereto so as to produce a slow burning at relatively low temperatures, generating a supply of hot burning gases from a separate source and mixing the same with an excess of air at a point removed from said chamber so that said materials in said chamber are not exposed to the heat generated, conducting the products of such slow burning out of such chamber and mixing the same with said hot burning gases and air at a point sufficiently removed from said materials so that the said products of such slow burning may be completely consumed without accelerating the burning of said materials.

5. A destructor for burning materials which may evolve objectionable smoke or fumes or are highly inflammable comprising in combination a heat supply chamber having therein means for supplying hot burning gases and air, a combustion chamber, a passage connecting said chamber through which said hot burning gases and air may pass into said combustion chamber, a burning chamber having a substantially imperforate hearth, said burning chamber being closed to prevent uncontrolled admission of an excess of air but provided with means for admitting a controlled limited supply of air in which said materials may be initially burned slowly and at low temperatures in said burning chamber isolated from the heating effect of said heat supply chamber, said burning chamber being spaced from the path of said hot burning gases so that said materials are not subjected to the direct heating action thereof, said burning chamber connected with said passage at a point remote from said materials so that the latter do not lie in the path of said hot gases, and an insulating wall for shielding said materials from the heat of said heat supply chamber.

ARTHUR H. MANN.
